MOISTURE DETERMINING APPARATUS

Harold W. Bartlett, Berkeley, Calif., assignor to
 Rosenberg Bros. & Co., San Francisco, Calif.,
 a corporation of California

Application November 2, 1938, Serial No. 238,383

5 Claims. (Cl. 175—183)

This application relates generally to apparatus for determining moisture content of various materials. In practice the invention has been successfully applied for accurate determination of moisture content of grains, like wheat, rice, oats, etc., and it can also be applied to a variety of food products and other material, including for example tobacco, various vegetables, dried fruits, like raisins, prunes and the like, nuts and other materials where it is desired to secure a 10 rapid and relatively accurate determination of moisture content without a specific moisture analysis.

In the past it has been known that the moisture content of various materials results in a change in electrical conductivity. Apparatus making use of this principle has met with some degree of success, particularly where no disturbing factors are involved, as for example the presence of water which is not evenly distributed throughout the mass. Where certain disturbing factors are involved, such as unequal distribution of moisture in the mass, moisture determination by electrical conductivity is inaccurate and cannot be relied upon. Furthermore, such apparatus can only be used with accuracy for a limited range of moisture content, and considerable care must be taken to maintain a sample under proper predetermined conditions of pressure in order to secure the desired results.

As an alternative to indicating the conductivity or resistance of a sample, it has also been proposed to measure moisture content conductivity by electrical apparatus serving to indicate the dielectric capacity of a given sample. The dielectric capacity or specific conductive capacity of various materials varies as the moisture content varies. However, apparatus based upon this principle such as has been used in the past has not been sufficiently critical for accurate moisture determination, and it has been applicable to a wide range of moisture content. According to my observations this is largely due to the effect of the resistance component offered by the sample upon the power factor of the electrical energy impressed upon the sample by the testing apparatus.

It is an object of the present invention to provide a moisture determining apparatus which operates by measuring dielectric capacity of a sample, and which will give accurate results for a wide range of moisture content. For example, the present apparatus will operate successfully for a range of moisture content from substantially zero to one hundred percent. Thus the present invention is applicable to both liquids and solids.

A further object of the invention is to provide apparatus of the above character which will not be detrimentally affected by extraneous factors

such as voltage variations upon the current supply line, and which will afford a positive and highly critical indication.

Additional objects of the invention will appear 5 from the following description in which the preferred embodiment of the invention has been set forth in detail in conjunction with the accompanying drawing.

Referring to the drawing:

Fig. 1 is a circuit diagram illustrating diagrammatically apparatus in accordance with the present invention.

Fig. 2 is a side elevation in cross section, showing a sampling device for use in connection with the present apparatus.

The apparatus as illustrated in the drawing makes use of a sample cell including a pair of spaced electrodes between which a sample of material may be placed. This cell is coupled to 20 a high frequency electrical oscillator generator in such a manner that the capacitance afforded by the cell forms a capacitive element of a resonant circuit which in turn determines the frequency of operation of the oscillation generator. 25 The resistance component afforded by the sample in the cell is effectively neutralized by virtue of the fact that the oscillation generator affords a negative resistance component.

Referring first to Fig. 1 of the drawing, the 30 apparatus illustrated includes the cell 10 for retaining the sample to be tested, and which is coupled to the electrical net work 11. The electrical net work includes the electron relays or vacuum tubes 12 and 13, which are arranged to 35 generate electrical oscillations, and the tubes 14 and 15, which are arranged to stabilize the frequency of oscillations generated. As will be presently explained connections to tubes 12 and 13 are preferably such that they operate as dynatron 40 oscillators. A dynatron oscillator of the electron relay type is one in which the plate is maintained at a lower potential than the screen grid and which employs the phenomenon of secondary emission to obtain a negative resistance.

The cell 10 as illustrated diagrammatically in 45 Fig. 1 includes the electrodes 17 and 18. Spaced plates can be utilized having their surfaces covered with suitable insulating material, and between which the sample of material may be placed. As illustrated diagrammatically in Fig. 1 and as will be presently described with reference to Fig. 2, it is preferable that one electrode, as for example electrode 17, be in the form of a tube or rod disposed axially of the outer tubular electrode 18. The outer electrode 18 is connected to ground 19, thereby tending to make operation of the cell immune with respect to surrounding objects such as the hand of the operator.

The tube 12 is preferably a tetrode having its plate 21 connected to one side of a resonant cir-

cuit which includes the inductance 22, and shunt condensers 23, 24 and 25. A switch 26 is shown for disconnecting condenser 25. The other side of inductance 22 connects to ground 28 through the high frequency by-pass condenser 29. A suitable source of plate potential is connected to the plate of relay 12, as for example a rectifier and filter 31 which can be supplied with alternating current. The positive lead from the rectifier and filter 31 is shown connected to the conductor 32, which in turn connects to the low potential side of inductance 22 through the resistor 33. The other end of this resistor is grounded. The screen 34 of relay 12 is connected directly to the lead 32 by conductor 36.

The grid or control element 37 of tube 12 connects with a stabilizing relay or vacuum tube 14. Thus grid 37 is shown connected to one side of the inductance 38, which is inductively coupled to the inductance 22. The other side of inductance 38 connects with the grid 39 of the relay 14. Cathode 41 of electron relay 14 together with cathode 42 of relay 12, connect to a common lead 43, which in turn is connected to ground through the high frequency by-pass condenser 44.

The electron relay or vacuum tube 13 is likewise shown as a tetrode, and is connected to circuits in such a manner as to form a dynatron oscillator. The plate 21 of tube 13 connects to one side of the inductance 46, which is shunted by the variable condenser 47. The other side of inductance 46 is directly connected to the corresponding side of inductance 22, by conductor 48. Likewise, the same side of inductance 46 is connected to ground 49 through the high frequency by-pass condenser 51. The screen 34 of electron tube 13 conductively connects to the lead 32, as with the tube 12. Likewise the grid 37 is grounded and is connected to one side of an inductance 32, which is inductively coupled with inductance 46 and has its other side connected with the grid 39 of tube 15. The cathodes 41 and 42 of tubes 15 and 13 connect to the common conductor 54, which in turn connects to ground through the high frequency by-pass condenser 56.

The negative side of the rectifier and filter 31 is grounded as indicated. The cathode conductors 43 and 54 connect to the biasing resistors 57 and 58 which in turn connect to ground 59. The plates 60 of the electron relays 14 and 15 both connect through resistors 61 and 62 to the supply lead 32.

As a convenient and effective type of indicating means, I have shown a "Crooks" tube type of visual indicating device 63, such as are used to indicate the tuning of radio broadcast receivers. The heated cathode 64 of this device is shown connected to ground through the resistor 66. The plate or anode 67 is directly connected to the supply lead 32. The screen 68 connects with plate 67 through the resistor 69. The control grid or element 71 is coupled to both the plates 60 of tubes 14 and 15, through the condensers 72 and 73. Also grid 71 is connected to ground through resistor 70. Device 63 affords an illuminated screen with a variable iris which indicates the additive potential obtained from the plate circuits of both the tubes 14 and 15. Also when two oscillation generators are operating at nearly the same frequency, whereby the beat or differential frequency is relatively low, as for example 10 cycles or less per second, this beat frequency is clearly indicated.

It will be evident that the capacitance afforded by the cell 10 will be determined in part by the

dielectric value of the material placed between the electrodes 17 and 18. Likewise for a given sample the cell as a whole assumes a given value of capacitance, which becomes a reactive element 5 of the resonant circuit which includes the inductance 22, and which controls the frequency of oscillations generated. Use of three condensers 23, 24 and 25 facilitates calibration and adjustment of the apparatus. In a typical instance where the samples range from zero to twenty-five percent moisture, condenser 23 may range from 0 to 25 mmf., condenser 24 from 0 to 100 mmf., and condenser 25 from 0 to 25 mmf. Condenser 25 is set at such a value that when the cell 10 is connected in the circuit but is empty, with the condenser 24 set at 50% of full value, the oscillations generated by tube 12 are absolutely in synchronism with the setting of oscillation generator 13. For the values just given for condensers 23, 24 and 25, condenser 47 across inductance 46 can afford a maximum capacitance of 150 mmf., and is adjusted to afford a given set frequency of operation, as can be determined by suitable calibrating instruments.

Before proceeding with an explanation of the apparatus, it can be pointed out that the frequency of operation of the tubes 12 and 13 is stabilized by electron relays 14 and 15. In this connection it will be noted that the bias resistor 57 for tube 14 is also the bias resistor for the tube 12. Thus any increase in excitation of the tube 14, resulting from an increase in self excitation of the dynatron formed by tube 12, causes an increased current flow through the common biasing resistor 57 with the result that there is a tendency for the bias upon the grid or tube 12 to increase to suppress self excitation. Therefore the frequency of operation of the dynatrons and the amplitude of the potentials repeated by the tubes 14 and 15 remain substantially constant. Also, although the dynatrons and the relays 14 and 15 are in push-pull relationship, there is no tendency for one dynatron to pull the other generator into synchronism.

Assuming that the apparatus has been properly adjusted and that one has the necessary calibration charts for interpreting readings obtained, a given sample is placed within the cell 10. With the network 11 in operation, the operator adjusts the variable condenser 24 and observes the indicating device 63, until this indicating device shows a beat frequency of minimum frequency and maximum amplitude. This means that the two dynatrons are operating at substantially the same frequency. The setting of condenser 24 can now be accurately translated into terms of moisture content by reference to the calibration charts.

Reference has been made to the fact that a dynatron oscillator is a negative resistance device, and that this serves to effectively neutralize the effect of the resistance component of the sample. In this connection it should be pointed out that negative resistance component of the 65 dynatron which is coupled to the sampling cell, should be less than the resistance of the sample itself. For example, where a sample affords a resistance of 4000 ohms, the negative resistance component afforded by the tube 12 should not be more than 4000 ohms. For samples containing more than say 25% moisture, it may be necessary to use two tubes operating in parallel, in order to secure a required negative resistance component of the required value. The negative resistance component makes the apparatus im-

mune to power factor losses such as would make ordinary apparatus inoperative or inaccurate for samples of relatively high moisture content.

In a typical apparatus operating as described above, for measuring samples varying from 0 to 25% moisture, including both solids and liquids, the frequency of operation of the dynatron tube 13 should be relatively high in order to secure the desired critical indication, as for example in the neighborhood of from seven to eight hundred thousand cycles. Portions of the network should be suitably shielded as is well known to those skilled in the art, in order that extraneous objects may not affect the frequency of operation or the accuracy of the results obtained. In actual operations I have found it practical to maintain the frequency of operation sufficiently constant so that the indicating device 63 indicates a beat frequency as low as one cycle per second.

Fig. 2 illustrates suitable structural details for the sampling cell. In this instance the inner electrode 17 is in the form of a metal tube, having its outer surface covered by the glass tube 76. The outer electrode 18 is in the form of a larger metal tube, having its axis coincident with the axis of electrode 17, and having its inner surface covered by the glass tube 77. The lower ends of both electrodes are attached to the common bottom wall or base 78, which carries a central contact stud 79 connected to the electrode 17.

The electrical network 11 previously described is generally enclosed within a suitable cabinet, with one wall of this cabinet carrying provision for connection with the cell 10. Fig. 2 illustrates one top wall of such a cabinet formed of a metal panel 81 which is grounded and which carries insulating cup 82. A quantity of mercury 83 is carried within cup 82 and connects with terminal 84. The upper side of the cup 82 is apertured to receive the contact stud 79, substantially in the manner illustrated. The lower edge of the outer electrode 18 is shown provided with depended buttons or studs 86, for making connection with the grounded metal panel 81. Thus the outer electrode 18 is connected to ground, while the inner electrode 17 is connected to the mercury in cup 82, which in turn makes connection with the electrical network 11 as illustrated in Fig. 1. In using the apparatus the cup 82 can receive a predetermined volume of the material, or if desired the cup can be always filled with the material, and then this amount of material accurately weighed after making a test and both the weight and the volume taken into account in determining moisture content.

The insulating covering 76 and 77 for the electrodes can be omitted, provided one inserts a suitable blocking condenser in series with the cup.

I claim:

1. In moisture testing apparatus, a sample cell including a pair of spaced electrodes between which a sample of material may be placed, a dynatron oscillator having a resonant circuit including said cell as a capacitive element of the same, electron relay means for stabilizing the frequency of operation of the dynatron, and means for indicating a given frequency of operation of the dynatron.

2. A moisture testing apparatus, a sample cell including a pair of spaced electrodes between

which a sample of material may be placed, a pair of dynatron oscillators, one of said dynatrons operating at a fixed frequency and the second having a resonant circuit including said cell as a capacitive element of the same, said resonant circuit also including a variable reactance whereby the dynatron associated with the same can be tuned by variation of said reactance to a condition in which it generates oscillations at the same frequency as the first dynatron, separate electron relay stabilizing means associated with said dynatrons and serving to stabilize the frequencies of operation of the same, and indicating means coupled to receive electrical oscillations from both said dynatrons and serving to indicate a critical condition in which both said dynatrons operate at the same frequency.

3. In moisture testing apparatus, a sample cell including a pair of spaced electrodes between which a sample of material may be placed, an electrical oscillation generator having negative resistance characteristics, said generator having a resonance circuit including said cell as a capacitative element of the same, whereby variations in the capacitance of said cell for different samples placed within the same affects the frequency of operation of the oscillation generator, means for stabilizing the frequency of operation of the oscillation generator, and means for indicating a given frequency of operation of the oscillation generator.

4. In moisture testing apparatus, a sample cell including a pair of spaced electrodes between which a sample of material to be tested may be placed, a pair of electrical oscillation generators each having negative resistance characteristics, one being capable of operation at a fixed frequency, and the second having a resonance circuit including said cell as a capacitative element of the same whereby a change in the capacitance of said cell for different samples of material affects the frequency of operation of the second oscillation generator, means for stabilizing the frequency of operation of both said oscillation generators, and indicating means coupled with both of said oscillation generators and serving to indicate generation of oscillations of substantially the same frequency by both said generators.

5. In moisture testing apparatus, a sample cell including a pair of spaced electrodes between which a sample of material may be placed, a pair of dynatron oscillators, one of said dynatrons operating at a fixed frequency and the second having a resonance circuit including said cell as a capacitative element of the same, said resonance circuit also including a variable reactance whereby the dynatrons associated with the same can be tuned by variation of said reactance to a condition in which it generates oscillations at the same frequency as the first dynatron, separate electron relay stabilizing means associated with said dynatrons and serving to stabilize the frequencies of operation of the same, and indicating means coupled to the outputs of said stabilizing means to receive electrical oscillations from both said dynatrons, said indicating means serving to indicate a condition in which both said dynatrons operate at the same frequency.

HAROLD W. BARTLETT.
